UNITED STATES PATENT OFFICE.

ALEXANDER DOUGLAS, OF NORTH FITZROY, VICTORIA, AUSTRALIA, ASSIGNOR OF
ONE-HALF TO HERBERT HENRY HODGSON, OF NORTH FITZROY, AUSTRALIA.

STAFF-EXCHANGER.

1,151,167.

Specification of Letters Patent. Patented Aug. 24, 1915.

Application filed August 26, 1914. Serial No. 858,716

To all whom it may concern:

Be it known that I, ALEXANDER DOUGLAS, a subject of the King of Great Britain, residing at 804 Brunswick street, North Fitzroy, in the State of Victoria, Commonwealth of Australia, have invented certain new and useful Improvements in Staff-Exchangers, of which the following is a specification.

The object of this invention is to provide staff exchangers adapted for fast traveling trains so that the exchange of staffs at appointed places on the line may be effected without necessarily reducing the speed of the train.

According to this invention one exchanger is provided on the engine of a train and the others at the side of the track at the positions where the staffs are to be exchanged.

The exchangers are similar in that they each have means to hold one staff in the required position and to release another staff, while each may be moved or folded to render it inoperative when not required.

The drawings illustrating the invention comprise—Figure 1 a sectional plan (broken) of the exchanger fixed to the engine, Fig. 2 an elevation and Fig. 3 an enlarged detail thereof; Fig. 4 a side elevation (broken) of the exchanger fixed at the side of the track and Fig. 5 a rear view. Fig. 6 is an enlarged detail of the staff and case and Fig. 7 a section on line VII—VII Fig. 6, while Fig. 8 is a diagrammatic view illustrating the application of the invention.

The exchanger on the engine E consists of a bar 1 preferably constructed as described hereinafter and extending forwardly. On the forward end are mounted two inclined hinged arms 2,3 supported on springs 4, 5. These arms are arranged one behind the other and the rearmost one is longer than the forward one and is provided at its upper end with stopping means, such as a hook 6 and lower down with a projection or retaining catch 7.

The staff 8, Figs. 6 and 7 is adapted to be placed in a case 9 preferably made of leather to which a ring or hoop of cable wire or the like 10 is connected by means of a flexible flap 11 made of leather for instance and strengthened by a metal clip 12 and the case is provided with a slight opening 13 (which may have a cover) to enable the name of a station marked on the staff to be

readily ascertained while the case also is provided with a cap 14 to retain the staff.

The staff case which is preferably round in section is adapted to be engaged with one or more spring jaws 15 provided on a projecting bracket 16 on the rear end of the bar 1 and if desired it is seated on a support 17 on said bracket so that the ring or hoop extends at right angles to the engine or the bar 1.

Means are provided for preventing rotation of the case in the jaws. This may consist of a spring 18 on the bracket adapted to bear upon a metal plate 19 provided on the cap of the case.

The exchanger above described is adapted to be swung into or out of its operative position by means of a lever 20 pivoted as at 21 to the side of the engine. Accordingly, the lower end of the lever is bifurcated to receive a link 22 also bifurcated and pivoted to an arm 23. The latter is pivoted as at 24 to the side of the engine and its other end is bifurcated to receive a lug 25 on the bracket 16 of the exchanger bar, said lug being pivoted on a bolt 26 passing through the bifurcated end of said arm 23. Another arm 27 is arranged parallel to said arm 23 and similarly connected with the bracket and the engine.

In order to swing up the exchanger on the engine the lever is moved in the direction indicated by an arrow (Fig. 2) when the exchanger is folded up into its inoperative position as indicated in dotted lines (Fig. 2).

The lever is supported by a chain 28 or the like when this part of the exchanger is in its operative position and retained by a hook 29 when in its inoperative position.

The exchangers arranged at the side of the track Figs. 4 and 5 each consists of a bar 30 secured to a vertical standard 31 on the ground. The forward end 30a of the bar is provided with spring controlled hinged arms 32, 33, hook 34 and catch 35 and the rear end is provided with jaws 36 all similar to the exchanger on the engine. The forward end is pivoted as at 37 to the rear part and secured to the latter by a pin or bolt 38. By means of this construction the forward end of the bar may be swung down when not required against the standard.

The standard may be made of two sepa-

rated angle irons which are pivoted as at 39 to a vertical lug 40 on the ground plate 41 and it is secured in its vertical position by a removable pin 42 and by a spring catch 43 engaging a small bar 44 on the standard. The lug 40 abuts against a stop 45 which takes the shock when the staffs are being exchanged.

After first swinging down the forward 10 end 30^a of the bar of the exchanger the pin 42 is removed and the catch 43 released when the standard may be folded down, into for instance, a casing (not illustrated) which may be kept locked to prevent unauthorized 15 interference.

The hinged arms on the bars 1 and 30 constitute an efficient shock absorbing means. These arms project into the path of the 20 hoop and yieldingly engage the latter in its movement along the rod so that a lateral strain on the arms 23 and 27 and the standard 31 is reduced to a minimum.

We claim:—

1. A staff exchanger comprising a forwardly projecting bar, inclined spring-supported arms hinged to said bar, a staff case, a hoop on the latter, and jaws on the rear end of the bar adapted to embrace the case and hold the hoop in receiving position.

2. A staff exchanger comprising a forwardly projecting bar, inclined spring-supported arms hinged to the forward portion of the bar, a staff case, a hoop connected to one side of the latter, and spring jaws on the 35 rear end of the bar adapted to embrace the case and hold the hoop at right-angles to the bar.

3. A staff exchanger comprising a forwardly extending bar, substantially parallel 40 inclined spring-supported arms hinged on the forward portion of the bar, the rear bar being longer than the other and having a hook at its rear end and a catch below the latter, a staff case having a hoop, and spring 45 jaws on the rear end of the bar adapted to support the case with the hoop at right angles to the latter.

4. A staff exchanger comprising a forwardly projecting bar, substantially parallel 50 upwardly inclined, spring-supported arms hinged to the forward part of said bar, jaws on the rear end of the bar adapted to embrace a staff case, and means for folding the exchanger into inoperative position.

5. A staff exchanger comprising a forwardly projecting bar, substantially parallel

upwardly inclined, spring-supported arms hinged to the forward part of said bar, jaws on the rear end of the bar adapted to embrace a staff case, and a lever for swinging 60 the exchanger into inoperative position.

6. A staff exchanger comprising a forwardly projecting bar, inclined spring-supported arms hinged on the forward portion of the bar, a bracket on the rear end of the latter, spring jaws on the bracket adapted to hold a staff case in receiving position, a pair of parallel arms pivotally connected to a support and to the bracket, a lever pivoted on the support, a link connecting the lever 70 to one of the parallel arms, and means for holding the lever in the operative or inoperative position.

7. A staff exchanger comprising a forwardly projecting bar, a pivoted support therefor, spring-supported buffer arms hinged on the support, and a bracket on the rear end of the bar, and spring jaws on the bracket adapted to hold the staff in receiving position.

8. A staff exchanger comprising a forwardly projecting bar constructed of two pivotally connected parts, a pin for holding said parts in alinement, inclined spring supported arms hinged to the forward portion of said bar, jaws adapted to hold a staff in its receiving position, a pivoted standard to which said bar is fixed, and means to hold the standard in a vertical position.

9. A staff exchanger comprising a forwardly projecting bar, inclined spring supported arms hinged on the bar, a bracket on the rear end of the bar, spring jaws on the bracket adapted to receive a case containing 95 the staff, a flexible hoop on the case, a support for the case on the bottom of the bracket, and a spring at the top of the latter to maintain the case in position.

10. In a staff exchanger, the combination 100 with a support for the staff case, of a rod for removing the case from its support, and a plurality of shock absorbing members mounted along the rod.

In testimony whereof I have hereunto set 105 my hand in presence of two subscribing witnesses.

ALEXANDER DOUGLAS.
